UNITED STATES PATENT OFFICE.

JOHN F. BURROUGHS, OF BALTIMORE, MARYLAND, ASSIGNOR TO T. R. GOODLATTE & SONS, INC., OF DELAWANNA, NEW JERSEY, A CORPORATION OF NEW JERSEY.

DESIGN FOR A TABLE COVER OR ANALOGOUS ARTICLE.

Application filed November 23, 1925. Serial No. 15,522. Term of patent 7 years.

To all whom it may concern:

Be it known that I, JOHN F. BURROUGHS, a citizen of the United States, residing at Baltimore, in the county of Baltimore and State of Maryland, have invented a new, original, and ornamental Design for a Table Cover or Analogous Article, of which the following is a specification, reference being had to the accompanying drawing, forming part thereof.

The figure is a plan view of a table-cover, showing my new design.

I claim:

The ornamental design for a table-cover or analogous article, substantially as shown.

JOHN F. BURROUGHS.
